Ind., assignors to Marbon Corporation, Gary,
Ind., a corporation of Delaware

Application July 16, 1938, Serial No. 219,670

2 Claims. (Cl. 23—285)

This invention relates to apparatus particularly adapted for treating solid material with liquids.

An object of the invention is to provide a quick and economical means for producing reaction products of solid material with liquid reagents.

Another object is to provide an apparatus for producing amorphous rubber hydrochloride in a continuous or semi-continuous manner.

Other objects and advantages of the invention will become apparent as the following detailed description progresses, reference being had to the accompanying drawings in which:

Fig. 1 is a front elevation, partly in section, of a preferred embodiment of the invention.

Fig. 2 is a side elevation, of Fig. 1, also partly in section.

Fig. 3 is a fragmentary view partly cut away showing the mechanism for operating the apparatus of the invention.

Fig. 4 is a detailed sectional view of the feed mechanism, and

Fig. 5 is a detailed sectional view of the feed mechanism showing a different position than in Fig. 4.

Referring to Figs. 1 and 2, the reference character 1 denotes a wheel having a plurality of receptacles 2 around its periphery. The wheel 1 is surrounded by and adapted to rotate in a cylindrical chamber 3, adapted to hold cold liquefied hydrogen chloride. This chamber 3 is protected by insulation 4 and has a conduit 5 for the admission of the liquid hydrochloride.

A conduit 6 having slide valve 29 is also connected to the top of the cylindrical chamber 3 and is adapted to receive bundles of rubber (7) and allows them to be fed through valve 29 into the receptacles 2 as the wheel 1 rotates and brings the empty receptacles in front of the opening 8 in the conduit 6 at the time valve 29 is open.

In the peripheral portion of the chamber 3, as shown in section in Fig. 2, is a piston-like pusher rod 9 having an end disc portion 11 adapted to contact bundles in the receptacles 2.

A second and larger cylindrical chamber 12, having inlet conduit 13 and overflow conduit 14, is positioned adjacent to the cylindrical chamber 3 and so that its upper periphery is slightly below the upper periphery of the cylindrical chamber 3.

Connecting the peripheral lateral portions of the cylindrical chambers 3 and 12 is a conduit

or passageway 15, as shown more clearly in Fig. 2, adapted to receive bundles pushed out of receptacle 2 by the pusher rod 9 and transfer the bundles into chamber 12. An exit pipe 28 for removal of hydrogen chloride is also connected to the passageway 15.

A wheel 16 is adapted to rotate within the cylindrical chamber 12. A plurality of prongs, 17, 18, 19, and 20 extend radially from the wheel 16 to within close proximity of the peripheral walls 21 of the cylindrical chamber 12. These prongs are spaced apart from each other in a direction parallel to the axis of the wheel to allow the passage of the prong 22 as the wheel rotates. Other prongs, 17a, 18a, 19a and 20a, and so forth, also extend radially from the periphery of the wheel 16 in spaced relationship around the periphery of the wheel. The series of prongs thus spaced around the circumference of the wheel form pockets or receptacles adapted to hold bundles 7R received from conduit 15.

Attached to the cylindrical chamber 12 is an exciting conduit 23 adapted to extend above the level of the liquid in the chamber 12. This conduit is bent at 24 in order to direct the bundles 7R downwardly through conduit 25 into shredder 26, thence into mixing tank 27.

Suitable motor means and auxiliary mechanism are used to rotate the wheels 1 and 16, to open and close the valve 29, and operate the pusher rod 9 in such synchronism that the unreacted bundles 7 will always drop into an empty receptacle in the wheel 1 as the reacted bundles 7R are removed from a receptacle in wheel 1 and transferred to an empty receptacle in wheel 16. This operating mechanism consists of a motor 30 having a chain drive 31 adapted to drive wheel 32. Wheel 32 has a tooth 33 meshing with gear wheel 34 which is secured to the axle 35 of the wheel 16. Also secured to the axle 35 is a gear 36 having a chain drive 37 meshing with gear 38, on axle 39 of wheel 1. On axle 40 carrying the gear wheel 32 is a cam member 41 adapted to contact projection 45 on rod 42, thereby causing the rod 42 to move downwardly as the wheel 32 rotates. This rod 42 is secured to the conduit 6 by a spring 43 adapted to pull the rod 42 upwardly when it is released by the cam 41. Attached to the rod 42 is a T-shaped rocker arm 44, as shown more clearly in Figs. 4 and 5. Attached to one end of the T is the pusher rod 9 having a piston 11 adapted to push against the bundle 7R. Secured to the pusher rod 9 is a slide valve 47, adapted to close the opening in

the conduit 6 as the bundle 7R is pushed out. This is shown more clearly in Fig. 5. At the other end of the T is the slide valve 29, adapted to close the opening in conduit 6 as shown more clearly in Figure 4.

It will be seen that as the wheel 32 and cam member 41 rotate the cam member 41 pushes the rod 42 downwardly, operating the rocker arm 44 and causing the pusher rod 9 and slide valve 47 to move to the right, and the slide valve 29 to move to the left, thereby allowing the bundles 7 to drop on to the slide valve 47 as shown in Fig. 5.

As the cam continues to rotate and comes out of contact with the projection 45 the rod 42 is released and moves upwardly because of the action of the spring 43, thus moving the pusher rod 9 and the slide valve 47 to the left and the slide valve 29 to the right as shown in Fig. 4. By this means the bundle held by the slide valve 47 is released and drops into the receptacle on wheel 1 as also shown in Fig. 4.

Meanwhile the wheel 32 is rotating but not meshing with gear wheel 34. Just before it completes one revolution it meshes with gear 34, causing the rotation of the wheel 1 just sufficiently to move the bundle 7 out of range of the pusher rod 9 and the bundle 7R into range of the pusher rod 9.

The process of making amorphous rubber hydrochloride in the apparatus of this invention is as follows:

The cylindrical chamber 3 is filled with liquefied anhydrous hydrogen chloride to about the level 28' as shown in Fig. 1. The cylindrical chamber 12 is filled with concentrated solution of hydrogen chloride and water to about the level indicated at 29' in Fig. 1. The wheels 1 and 16 are then rotated by motor means 30 shown. Rolls of rubber 7 consisting of corrugated sheets of pale crepe are placed in the conduit 6 and drop down into the receptacles 2 of the wheel 1 when the valve 29 opens on every revolution of the wheel 1. Likewise as the wheel rotates, the bundles 7 are immersed in the liquefied hydrogen chloride and react with it, producing bundles of amorphous rubber hydrochloride 7R. As these bundles 7R emerge from the liquefied hydrogen chloride they are pushed out of the receptacle 2 by the motor operated pusher rod 9 and disc 11 into the conduit 15 where they fall into the pockets in the wheel 16 as this wheel 16 rotates.

The rotation of the wheel 16 carries the bundles 7R down into the concentrated hydrochloric acid. As the bundles 7R travel through this hydrochloric acid they are raised in temperature, due to heat transfer between the bundles and the hydrochloric acid. This heating of the rubber hydrochloride vaporizes the excess hydrochloride liquid which is then recovered directly through exit 28. On emerging from the hydrochloric acid the bundles 7R contact the rod 22 and are directed up into the conduit 23, thence down through the conduit 25 into the shredder 26, each bundle being pushed over the bent portion 24 by the succeeding bundles as they are

released from the pockets of the wheel 16. The bundles are ground in the shredder 26 into granulated rubber hydrochloride. The ground rubber hydrochloride is removed from the shredder and washed with water in the mixing tank 27.

While there have been shown and described certain embodiments of the invention, it is to be understood that it is capable of many modifications. Changes, therefore, may be made without departing from the spirit and scope of the invention as described in the appended claims, in which it is the intention to claim all novelty inherent in the invention as broadly as possible, in view of the prior art.

15 We claim:

1. In an apparatus of the class described, a wheel having a plurality of receptacles around its periphery, a cylindrical chamber enclosing said wheel but spaced apart from the periphery of the wheel so as to allow the wheel to rotate through fluid which may be held in said chamber, a second wheel having a plurality of receptacles around its periphery, a cylindrical chamber enclosing but spaced apart from the periphery of said second wheel adjacent said first chamber, means for maintaining a first liquid at a definite level in the first chamber, means for maintaining a second liquid at a definite level in the second chamber, a passageway extending from the lateral peripheral portion of one chamber to the lateral peripheral portion of the other chamber at points above the liquid level in each, whereby solid material in the receptacles of one chamber may be transferred to the receptacles in the other chamber, means to eject said solid material from one of said receptacles of said first wheel, means associated with said ejecting means to feed a predetermined amount of solid material to said evacuated receptacle, and means to intermittently advance said first wheel so that another receptacle is adjacent said ejecting and feeding means.

2. In an apparatus of the class described, a wheel having a plurality of receptacles around its periphery, a first chamber for said wheel so as to allow the wheel to rotate through fluid which may be held in said chamber, a second wheel having a plurality of receptacles around its periphery, a second chamber for said second wheel and adjacent said first chamber, means for maintaining a first liquid at a definite level in the first chamber, means for maintaining a second liquid at a definite level in the second chamber, a passageway communicating with each chamber at a point above the liquid levels therein, whereby solid material in the receptacles of one chamber may be transferred through said passageway to the receptacles in the other chamber, means to eject said solid material from one of said receptacles of said first wheel into said passageway, means associated with said ejecting means to feed solid material to said evacuated receptacle, and means to intermittently advance said first wheel so that another receptacle is adjacent said ejecting and feeding means.

HENRY F. IRVING.
FLOYD E. WILLIAMS.
